[57] CLAIM

The ornamental design for a cutter knife holder, as shown and described.

DESCRIPTION

FIG. 1 is a perspective view of a cutter knife holder showing my new design;

FIG. 2 is a top plan view thereof;

FIG. 3 is a front elevational view thereof;

FIG. 4 is a bottom plan view thereof;

FIG. 5 is a rear elevational view thereof;

FIG. 6 is a left end view thereof;

FIG. 7 is a right end view thereof; and,

FIG. 8 is a perspective view thereof with a knife blade and a knob which are shown by broken lines.

The broken line showing of the knife blade and knob in FIG. 8 is for illustrative purposes only and forms no part of the claimed design.
